LAWN MOWER MOTOR SHROUD

James B. Stewart, Glen Ellyn, and Richard S. Hart,
Wheaton, Ill., assignors to Sunbeam Corporation, Chi-
cago, Ill., a corporation of Illinois

Filed May 24, 1967, Ser. No. 7,251

Term of patent 14 years

(Cl. D40—1)

Fig. 3.

Fig. 4.

Fig. 5. ← 7.

Fig. 6.

Fig. 7.

FIG. 1 is a perspective view of a lawn mower motor shroud embodying our new design;

FIG. 2 is a front elevational view thereof;

FIG. 3 is a rear elevational view thereof;

FIG. 4 is a side elevational view thereof;

FIG. 5 is a top plan view thereof;

FIG. 6 is a fragmentary sectional view taken substantially on line 6-6 of FIG. 5; and

FIG. 7 is a fragmentary sectional view taken substantially on line 7-7 of FIG. 5.

The broken lines shown in FIG. 1 are for illustrative purposes only.

We claim:

The ornamental design for a lawn mower motor shroud, as shown and described.
